[21] Appl. No.: 247,103

[57] CLAIM

[22] Filed: Mar. 24, 1981

The ornamental design for a zodiacal cusp medallion, as
shown and described.

DESCRIPTION

[62] Division of Ser. No. 58,730, Jul. 17, 1979, Pat. No. Des.
263,384.

The FIGURE is a front elevational view of a zodiacal
cusp medallion showing my new design, the medallion
being of conventional thickness and having the back
thereof plain.
